CLAIM

The ornamental design for a golf putter, as shown and described.

DESCRIPTION

FIG. 1 is a perspective view of a golf putter having our design;

FIG. 2 is a front view of the golf putter of FIG. 1;

FIG. 3 is a rear view of the golf putter of FIG. 1;

FIG. 4 is a left side view of the golf putter of FIG. 1;

FIG. 5 is a right side view of the golf putter of FIG. 1;

FIG. 6 is a top view of the golf putter of FIG. 1;

FIG. 7 is a bottom view of the golf putter of FIG. 1; and,

FIG. 8 is an enlarged top view taken on circle 8 of FIG. 6. Portions of the golf putter shown in broken lines form no part of the design claimed.

The dash-dot lines in FIGS. 2 and 5-8 are included as boundary lines and form no part of the claimed design.

Portions of the design shown with stippling indicate a contrasting shade or color from non-stippled portions.
